Attorney.

UNITED STATES PATENT OFFICE.

ADOLFO POUCHAIN, OF TURIN, ITALY.

MANUFACTURE OF CELLULOID VESSELS.

Application filed August 18, 1920. Serial No. 404,445.

To all whom it may concern:

Be it known that I, ADOLFO POUCHAIN, a subject of the King of Italy, and resident of Turin, Italy, have invented certain new and useful Improvements in the Manufacture of Celluloid Vessels, of which the following is a specification.

This invention relates to the manufacture of vessels of celluloid reinforced with internal layers of fabric by superimposing on a suitable mould successive layers of fabric impregnated with a solution of celluloid, to which may be added inert substances incapable of attack by dilute sulphuric acid, such as sawdust, talc or asbestos.

In the accompanying drawing is shown a mode of making an electric accumulator cell in accordance with this invention.

In said drawing Figure 1 is a perspective view of the cell in the course of manufacture; Figure 2 is a like view of the finished cell.

The core 1 is generally of wood and of several pieces to facilitate its extraction from the finished cell. On this core, covered for example with paper to avoid adhesion, there are wrapped successive layers of fabric 2, such as cloth, which are impregnated with a solution of celluloid, if necessary with addition of inert materials, until a thickness corresponding with that required for the bottom and sides of the cell has been attained.

Said solution of celluloid is obtained by dissolving celluloid in acetone, in the well known manner.

The mouth of the cell is made by threading on to the core, after several layers of fabric have been applied, a rigid frame 3 of metal, wood or other suitable material and the portions of the fabric which come close to this frame are preferably folded over it so as to cover it. When the celluloid has solidified the core 1 is removed and there is obtained a rigid cell, the walls of which are formed of celluloid with an internal reinforcement of fabric. Thus the cell is unbreakable and impermeable and may be ren-

dered uninflammable if it be treated with a non-inflammable varnish.

The finished cell is shown in Figure 2, from which it will be seen that owing to the rigid frame 3 the mouth of the cell is not liable to be deformed during the solidification of the celluloid.

The vessel may be made in this manner of any form and size desired, and is particularly suitable as a cell for electric accumulators because celluloid is not attacked by the electrolyte and is also light and unbreakable.

What I claim as my invention and desire to secure by United States Letters Patent is:—

1. A method of manufacturing vessels of celluloid comprising wrapping on a core successive layers of fabric impregnated with a solution of celluloid, inserting a rigid frame on said wrapped layers, permitting said celluloid to dry and removing said core.

2. A method of manufacturing vessels of celluloid comprising wrapping on a core successive layers of fabric impregnated with a solution of celluloid, inserting a rigid frame on said wrapped layers at the mouth of the vessel, permitting said celluloid to dry and removing said core.

3. A method of manufacturing vessels of celluloid comprising wrapping on a core successive layers of fabric impregnated with a solution of celluloid, inserting a rigid frame on said wrapped layers at the mouth of the vessel and over-turning the edges of said layers on said frame, permitting said celluloid to dry and removing said core.

4. As a new article of manufacture, a vessel comprising fabric impregnated with celluloid and having a rigid frame at its mouth.

5. As a new article of manufacture a vessel comprising fabric impregnated with celluloid and having a rigid frame incorporated at its mouth.

Signed at Turin, Italy, this 29th day of July, 1920.

ADOLFO POUCHAIN.
